(57) **CLAIM**

The ornamental design for a match receptacle, as shown and described.

DESCRIPTION

FIG. 1 is a perspective view of the match receptacle, illustrating our new design;

FIG. 2 is a right elevational view of the match receptacle of FIG. 1;

FIG. 3 is a left elevational view of the match receptacle of FIG. 1;

FIG. 4 is a front elevational view of the match receptacle of FIG. 1;

FIG. 5 is a rear elevational view of the match receptacle of FIG. 1; and,

FIG. 6 is a top plan view of the match receptacle of FIG. 1. Unshaded portions of the drawing figures enclosed within broken lines form no part of the claim, and structures illustrated in broken lines without shading are environmental structures that also form no part of the claim.

1 Claim, 6 Drawing Sheets
